(57) **CLAIM**

The ornamental design for a health tape, as shown and described.

DESCRIPTION

FIG. 1 is a front, left, bottom perspective view of a health tape showing our new design;

FIG. 2 is a front, left, top perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the health tape that form no part of the claimed design.

1 Claim, 8 Drawing Sheets
